UNITED STATES PATENT OFFICE.

GEORGE LITTLE, OF HUDSON CITY, NEW JERSEY, ASSIGNOR TO HIMSELF AND MARSHALL LEFFERTS, OF NEW YORK.

IMPROVEMENT IN APPARATUS FOR PERFORATING PAPER FOR TELEGRAPHING.

Specification forming part of Letters Patent No. 91,240, dated June 15, 1869.

To all whom it may concern:

Be it known that I, GEORGE LITTLE, of Hudson City, in the county of Bergen and State of New Jersey, have invented, made, and applied to use a certain new and useful Improvement in Apparatus for Perforating or Embossing Paper for Telegraphic Purposes; and I do hereby declare the following to be a full, clear, and exact description of the said invention, reference being had to the annexed drawing, making part of this specification, wherein—

Figure 1 is a general plan of the said apparatus. Fig. 2 is a side elevation with part of the bed and frame-work removed. Fig. 3 is a transverse section at the line $\pi\pi$ through the punching apparatus, and Fig. 4 is a section through the hub of the actuating-lever and handle.

Similar marks of reference denote the same parts.

This invention is designed for perforating or embossing paper for transmitting pulsations of electricity for telegraphic purposes.

The device I have shown in the drawings is particularly adapted to the perforation or embossing of characters to represent numbers for the commercial code of signals now employed in lessening the amount of matter transmitted; but the same mechanism might be employed for perforating or embossing paper for letter-characters if the instrument were proportionately enlarged or extended.

In my instrument I make use of a lever that is swung to place, and then by a pressure upon it at the same time that it is pushed forward the electric circuit is closed, and the pulsations of electricity communicated by alternate conducting and non-conducting surfaces over which the lever passes.

The movement of the lever, during the time the pulsations are being sent, also causes a movement of the paper the required distance for the space of the signal or letter perforated or embossed.

The perforation or raising of the paper is effected by a punch that is moved by magnetism, and the paper is momentarily stopped for each perforation by a secondary magnet that is brought into action by the movement of the punch to stop the feed-wheel for the paper.

In the drawing, a is a bed carrying the ver-

tical shaft b , set in a frame, c , at the upper end. On this shaft b is a hub, b' , around which is the eye c' of the lever c^2 , and between the hub b' and the eye c' are the clamping-segments 2 2. The inside of the eye c' is formed with a concave groove, and the outside of the segments 2 2 is convex to correspond therewith.

When the lever c^2 is horizontal, the eye c' turns freely around the clamps 2, as the lever is swung but by depressing the end of lever c^2 the clamps 2 are by the convex and concave surfaces forced upon the hub b' and gripe the same, and cause the shaft b and lever c^2 to move together.

Upon the bed a is a circuit-closer, formed of a raised segment, d , insulated from the bed a , and the surface of said circuit-closer is formed of conducting-bars of platina or other metal, filled in between with gutta-percha or other non-conducting material.

Upon the lever c^2 is an insulated spring, e , with the point resting upon the segment d , and above this is the screw 3.

Between the groups of conductors in the segment d , forming the letter or number, are radial grooves, cut as at $e' e'$.

The operator swings the lever c^2 until it comes to the given letter or number, as shown upon the circuit-closer segment, and as soon as the end of the spring clicks into the notch or groove e' he depresses the end of the lever, which brings the screw 3 into contact with the spring e , and closing that part of the circuit between the battery-wire f to the bed of the machine and lever c^2 , so that when the end of the spring e passes in contact with the metal conducting rib or ribs of d the proper electrical pulsations pass through the insulated segment d , and, dividing, pass through the wires 5 5 and the coils of the magnets $g g$ to the battery-clamping screw 6. The end of the spring dropping into the notch indicates by the touch or sound that the particular number or letter-character has been gone over, and he relieves his pressure on the handle c^2 , breaking the circuit between the screw 6 and the insulated spring e , bearing down upon the lever c^2 , clamps the shaft b , and moves that during the time that the lever is moving from one notch e' to the next. This effects the movement of the paper, as hereafter described.

The adjustable roller h , taking upon the sur-

face of the bed *a*, regulates the point to which the lever *c*² may be depressed.

I provide a blank space at *d*', so that the lever *c*² will be brought to this point after each number is perforated, and there depressed and moved horizontally to feed the paper without any pulsation of electricity passing through the magnets *g g*.

I provide a die, *7*, at the upper end of a hollow standard, *k*, supported on the bed *a*, and around this is a sliding tube, *l*, with arms *l*', to the armatures *m* of the magnets *g g*, and above the arms *l*' a yoke, *n*, carries the punch *i*. This yoke *n* has openings through its lower part at *9* for the strip of paper to pass through, as seen by red lines in Fig. 3. As the magnets are charged the armatures *m* are drawn down and the punch *i* struck through the paper into the die *7*. The armatures and punch are thrown up by the spring *8*. Rapid punctures of the paper will make a dash-opening, one perforation cutting into another. Dot perforations are formed by the paper moving a short distance between the perforations. This is effected by the conducting-bars of the segmental circuit-closer being so arranged and spaced as to give the pulsations of electricity at the proper intervals as the lever is moved over the same and the paper simultaneously actuated.

At the upper end of the shaft *b* is a gear-wheel, *o*, taking a pinion, *o*', on the shaft *p*, at one end of which are the feeding-disks *q q*, coming on each side of the yoke *n* and into contact with the paper that passes between them and the upper end of the standard *k*. I find that these feeding-disks are the best when each is made of two fine-cut circular saws, set with the teeth standing in opposite directions.

A spring-roller, *r*, serves to press the strip of paper to the disks *q* and insure the proper feed of the same; and I remark that the paper might be fed in either direction, according to whether the operator presses the lever *c*² down, when it arrives at the notch on the right side of the number or letter-character on the segment *d*, and then moves the lever toward the left to move and punch the paper, or whether he commences at the left-side notch and moves the lever to the right. The paper may be led as shown by the dotted red line instead of in the manner shown by the full red line.

Under the yoke *n*, I place the spring-stripper *s*, that has a motion limited by the pins *10*, and pushes the paper off the end of the punch as the punch rises.

The standard *k* is held within a stationary exterior sleeve, *k*', fastened to the bed *a*, and a very slight end motion is allowed at the point *11*, so that the standard *k* may be pressed down against the spring *t* sufficiently to allow the paper to be passed in between the upper end of *k* and the disks *q q*.

The operation of punching the paper with perforations corresponding in position to the

circuit-closers on *d* of the respective letters will be apparent from the foregoing, for it will be seen that the movement of the lever *c*² simultaneously makes and breaks the circuit to the punching-magnets and feeds the paper the proper distance for the perforations; hence the movement will be very rapid and easily performed.

It is necessary, however, to prevent the paper being in actual motion at the moment of the perforation, because if it were moving the cut would not be clean, but there would be a burr raised on one side of the hole. To effect this I employ magnets *u u*, with loose soft-iron pins, forming self-acting extension-poles within the magnet itself, as seen at *r*, and these lie close at the side of one of the feeding-disks *q*.

I employ an independent electric circuit from a second battery, through the binding-screws *v*¹ *v*², to the magnet-helix *u*. The spring-closer *w* is placed in this circuit, and the arm *14* on the sleeve *l* closes the circuit to *u* the moment the punch descends and begins to act on the paper. The extension-poles *v* becoming magnetized instantly, attach themselves to the side of the disk *q*, and momentarily arrest the feed of the paper until the punch *i* rises sufficient to clear the paper and break the circuit at *w*.

The friction on the hub *b*' allows the lever *c*² to be moved, while the feed-disks are momentarily stopped, or the feed-disks might themselves be mounted upon a friction-hub or disk.

It will be seen that the extension-poles become a brake to stop the feeding mechanism, and this character of a brake might be applied in other electrical apparatus.

What I claim, and desire to secure by Letters Patent, is—

1. The segment *d* and lever *c*², constructed and applied substantially as specified, to give the electrical pulsations for the respective characters by the movement of the one lever, substantially as set forth.

2. The lever *c*², fitted to swing on the shaft *b*, and provided with a friction-clamp to move the shaft *b* and effect the feed of the paper when the lever *c*² is depressed to close the circuit, substantially as set forth.

3. The punch *i*, set in the yoke *n* upon the arms *l*', in combination with the vertical standard *k*, carrying the die *7*, substantially as set forth.

4. The feeding-disks *q*, arranged to act on each side of the punch *i* against the standard *k*, substantially as set forth.

5. The standard *k*, sustained in the tube *k*', and fitted so that a slight end movement can be given to the same, in combination with the feeding-disks *q*, for the purposes set forth.

6. The magnet *u* and loose or self-adjusting extension-poles, forming a brake or stop, substantially as set forth.

7. The magnets *u* and extension-poles *v*, in

combination with the feeding mechanism, punch, and circuit-closer *w*, substantially as and for the purposes set forth.

8. A single punch for perforating and embossing paper for a telegraphic communication, actuated by the direct action of an electro-magnet, in combination with mechanism for giving motion to the paper between the various perforations forming the letters or characters, substantially as set forth.

In witness whereof I have hereunto set my signature this 7th day of December, A. D. 1868.

GEORGE LITTLE.
